UNITED STATES PATENT OFFICE.

GEORGE P. CRAGIN, OF FERGUS FALLS, MINNESOTA, ASSIGNOR, BY DIRECT AND MESNE ASSIGNMENTS, TO C. D. BAKER AND IDA L. CRAGIN, BOTH OF SAME PLACE.

NUT-LOCK.

SPECIFICATION forming part of Letters Patent No. 340,662, dated April 27, 1886.
Application filed January 5, 1886. Serial No. 187,643. (No model.)

To all whom it may concern:

Be it known that I, GEORGE P. CRAGIN, a citizen of the United States, residing at Fergus Falls, in the county of Otter Tail, State of Minnesota, have invented certain new and useful Improvements in Nut-Locking Bars, of which the following is a specification, reference being had therein to the accompanying drawings.

10 My invention relates to a nut-locking bar; and it consists in the construction and arrangement of the same, which will be more fully hereinafter described, and pointed out in the claim.

15 The object of my invention is to provide a nut-locking bar for holding nuts in such a position on railroad-rails and in other similar places that they cannot turn or become displaced from their bolts, which bar is simple 20 in its construction, strong and durable, and easily secured in its position. I attain these objects by the device illustrated in the accompanying drawings, wherein like letters of reference indicate similar parts in the several 25 views, and in which—

Figure 1 is a perspective view of a portion of a rail, illustrating the joint thereof with an angle-plate secured in position, and Fig. 2 is a perspective view of my improved nut-locking bar detached. Fig. 3 is a sectional plan view of a modified form of the lower half of the bar illustrated in Fig. 2. Fig. 4 is a sectional plan view of the lower half of a bar adapted to be used in connection with a fish-plate. Fig. 5 is a similar view of a modified 35 form of the lower portion of the bar illustrated in Fig. 4.

A indicates a portion of a rail showing a joint with the angle-plate B set in position 40 over the joint.

C represents the nuts of the securing bolts, which pass through the rail A and angle-bar B, and under which my improved locking-bar D is placed, said locking-bar being secured to the sleepers E by suitable means. The locking-bar D is constructed of suitable thin metal—such as sheet-iron or the like—and is first cut 45 in the desired form and then bent into an

angular shape. This locking-bar D is provided with two end projections, d d, which have their outer sides formed with slots d' d', through which spikes may be driven to secure it to the sleepers E. These end projections, d d, are connected by a lower web, d², which is recessed or cut away to form the said end seats, being of less transverse breadth than said seats, allowing the seats to extend outwardly beyond the web d². The under side of this web rests upon the angle-plate B, or upon the flange of the rail direct when a fish-plate is used. Bent at an angle to this web d² is another web, d³, which has a series of nut-seats or side washers, d⁴, which extend outwardly beyond the web d³, each having a space, d⁵, cut out between the same. 65

In Fig. 3 a modified form of the securing projections d d is illustrated. Instead of having the one side of the recesses or slots d' open, the said slot is cut into the metal and left open only in the front portion of the bar. 70

In Fig. 4 a form of bar is shown which is adapted to be applied in connection with a fish-plate. The lower securing-half is represented only, and in this instance the seats d are constructed near the center of the bar, so as to give a double-securing means on a single tie or sleeper. 75

In Fig. 5, a modified form of this portion of the bar, as represented in Fig. 4, is shown. In this instance the slots d' are constructed in a manner similar to the modified form of slots d'. (Shown in Fig. 3.)

To apply my improved nut-locking bar, the operation is as follows: The angle-plate B, or the fish-plate, having been secured over the joint in the rail A, and the nuts C, with their lower faces on a true line, screwed home, the locking-bar D is placed under the lower faces of the nut C. Then, by a suitable lever of pressure, the locking-bar D is pressed into position, each nut C bearing the seats or side washers, d⁴, down sufficiently to allow the locking-bar d to be pressed under the nuts C and into position, and then secured to the sleepers E by spikes driven through the recesses d', formed in the projections d. When the locking- 95

Bar is in this position the end or central projections will rest firmly on the angle plate or rail, and against the vertical portion of the angle-plate or fish-plate.

An important feature of my invention is the resilient force of the bar to hold and keep the nuts in place when loosened or displaced by the jarring caused by passing trains or from other causes. The bar being cut out of sheet metal and then bent into shape gives it a resilient force to resist the slightest movement of the nut and force it back into place and hold it there. This result cannot be obtained in locking-bars made solid of cast, malleable, or wrought iron, as such bars possess very little if any resiliency. This locking-bar is light and simple in its construction, dispensing with the use of a large quantity of metal, and thus avoiding the casting or construction of a cumbersome and heavy bar.

A further advantage of this bar is that it conforms to the contour and arrangement of any angle-plate or fish-plate, or the variation caused by the use of different sizes of nuts, or by adjustment of same, thus avoiding the necessity of constructing it to fit the plate to which it is desired to apply it.

It is obvious that any form of nut can be

readily used in construction with this bar other than those shown and described without changing the form of the bar and necessitating a departure from the nature and principle of my invention.

I am aware that locking-bars have been used in connection with angle and fish-plates, which are constructed to conform to the shape of the plate used, and such I do not claim; but

What I do claim as new, and desire to secure by Letters Patent, is—

As an article of manufacture, a nut-locking bar made of sheet metal and having two end projections in the lower portions thereof connected by a recessed web, a top web bent at an angle to the lower web and having a series of projections forming side washers for the nuts, formed by recesses in the upper web, and means for securing the bar when in position, substantially as described.

In testimony whereof I affix my signature in presence of two witnesses.

GEORGE P. CRAGIN.
